CLAIM

The ornamental design for a floor lamp, as shown and described.

DESCRIPTION

FIG. 1 is a front perspective view of a floor lamp showing my new design;

FIG. 2 is a rear perspective view of FIG. 1;

FIG. 3 is a front perspective view of FIG. 1;

FIG. 4 is a rear perspective view of FIG. 1;

FIG. 5 is a left side elevational view of FIG. 1;

FIG. 6 is a right side elevational view of FIG. 1;

FIG. 7 is a top plan view of FIG. 1; and,

FIG. 8 is a bottom plan view of FIG. 1.

The floor lamp is shown with a symbolic break in its length.

The appearance of any portion of the article between the symbolic break forms no part of the claimed design.

The broken lines shown in the drawings are included for the purposes of illustrating portions of the floor lamp that form no part of the claimed design.
